UNITED STATES PATENT OFFICE.

CHARLES MENDLER, OF SAN FRANCISCO, CALIFORNIA.

SECURING MEANS.

1,412,480.

Specification of Letters Patent. Patented Apr. 11, 1922.

Application filed August 2, 1921. Serial No. 489,294.

To all whom it may concern:

Be it known that I, CHARLES MENDLER, a citizen of the United States, residing in the city and county of San Francisco and State 5 of California, have invented a new and useful Improvement in a Securing Means, of which the following is a specification.

My invention relates to improvements in securing means for buttons provided with a 10 shank adapted for insertion through fabric particularly with respect to lapel buttons such as the emblems of fraternal orders and the like.

The primary object of my invention is to 15 provide an improved securing means arranged to engage the shank of a button to removably secure said button in position.

Another object of my invention is to provide an improved clamp adapted to facilitate 20 the placing and removing of a button from a lapel or other place of mounting.

A further object is to provide a securing means for use with buttons having smooth 25 straight shanks to eliminate the cost of threading and tapping in manufacture.

A still further object is to provide a device of the character described which is efficient and durable and which may be manufactured at a low cost.

50 I accomplish these and other objects by means of the device disclosed in the drawings forming a part of the present specification wherein like characters of reference are used to designate similar parts throughout said specification and drawings, and in which:

Fig. 1 is a rear elevation of my improved securing means drawn upon an enlarged scale.

40 Fig. 2 is a front elevation of Fig. 1.

Fig. 3 is a side elevation of the device as applied to the shank of a button.

Fig. 4 is a broken vertical section of the securing means as shown in Fig. 3.

45 Fig. 5 is a section taken along the line 5-5 of Fig. 1 in the direction indicated, the shank of a button being shown in engaged position.

Referring to the drawings my improved 50 securing device is seen to comprise a clamping member designated in general by the numeral 1 and a backing member designated in general by the numeral 2.

The clamping member 1 is stamped from 55 spring steel or other suitable material to form an annular ring 3, the material form-

ing the inner portion of the ring being offset from the plane of the ring and shaped to form a pair of clamping elements 4 having proximate edges 6 provided with oppositely disposed and centrally positioned recesses 7 forming an aperture 8. In the preferred construction illustrated in the drawings and best shown in Fig. 1, the elements 4 are formed by severing the offset portion for the greater part of its diameter, leaving oppositely disposed attaching strips 9. A central aperture is punched and the two clamping portions severed along diagonal lines tangent to the aperture. Extensions 11 are formed upon the elements 4, the outer ends of which are offset as at 12 to form gripping edges by which the elements may be sprung outwardly.

The backing member is stamped from 75 sheet metal or other suitable material to form a ring 14 having an annular flange 16 adapted to fit around the ring 3 and to be crimped thereover to form an annular rim. A diametrically disposed band 17 having 80 an enlarged portion 18 in which is punched or otherwise formed an aperture 19 extends between opposite sides of the ring 14 to give strength and rigidity to the rim and to provide a flat surface adapted to be pressed 85 against back of a lapel or other object to which a button is to be secured.

While my invention is capable of a broader interpretation to include any button having a shank, I have illustrated my improved securing means and will describe the operation of the device in connection with a lapel pin, for which purpose it is particularly designed and adapted. The numeral 21 is used to designate in general any lapel button such as the emblem of a fraternal order or the like upon which is provided a smooth straight shank 22 pointed at the end as at 23. When it is desired to secure the button 21 upon a lapel, the shank is inserted through the fabric and my device pushed onto the protruding point 23, the flat surface of the band 17 being presented to the back of the lapel.

The aperture formed by the recesses 7 is of a diameter slightly less than the diameter 105 of the shank 22 so that as the device is crowded over the point 23, the gripping elements 4 will be forced outwardly to admit the shank, the spring resilience of the metal serving to hold the contacting edges of the recesses in frictional engagement with the shank 22. The securing device is advanced 110

along the shank until the fabric of the lapel is firmly engaged between the band 17 and the back of the button 21 thereby holding said button in position.

- 5 As the clamping elements 4 are outwardly offset, any force tending to move the securing means rearwardly along the shank will operate to move the edges of the recesses 7 into firmer engagement with the shank 22, thereby effectually preventing removal of the shank. When it is desired to remove the button from the lapel, the extensions 11 are gripped between the fingers of the person desiring to remove the button and sufficient pressure applied to move the gripping edges outwardly as shown in dotted lines in Fig. 5, thereby releasing the frictional engagement with the shank 22 and permitting the button to be readily withdrawn.
- 10 20 It is desired to particularly emphasize the ease with which my device may be manufactured, the clamping and backing elements being each readily stamped from sheet metal and assembled by a simple crimping operation. The offset members 4 provide a powerful clamping means which will effectually prevent loss of either the button or the securing means, and the rigid construction insures an efficient and durable device. It is 25 furthermore particularly noted that the button shank need not be threaded and the securing means does not require tapping. This reduces the cost of manufacture both 30 of the button and the securing device. To 35 insert the smooth shank through the fabric and push my novel securing device over the end of the shank requires but an instant of time and may be accomplished with a minimum of inconvenience, thus affording a distinct improvement over the threading of a tapped retaining element onto a threaded shank as has been the common practice.
- 40 Having thus described my invention what I claim as new and desire to secure by Letters Patent is:
- 45 1. The combination with a button having a shank adapted for insertion through fabric and the like, of a securing member having securing means formed integral therewith and arranged to removably engage said shank to retain said button in position upon said fabric.
- 50 2. The combination with a button having a straight shank adapted for insertion through fabric and the like, of a securing member having securing means formed integral therewith and arranged to frictionally engage said shank to removably retain said button in position upon said fabric.
- 55 3. The combination with a button having a straight shank adapted for insertion through fabric and the like, of a securing member having a pair of proximate clamping elements formed integral therewith and arranged to frictionally engage said shank

to removably retain said button in position upon said fabric.

4. The combination with a button having a straight shank adapted for insertion through fabric and the like, of a securing member having a pair of proximate clamping elements oppositely recessed to form an aperture of a diameter slightly less than the diameter of the shank to frictionally engage said shank to retain said button in position upon said fabric.

5. The combination with a button having a shank adapted for insertion through fabric and the like, of a securing member comprising a rim; a pair of clamping elements formed integrally with said rim, said elements having proximate edges oppositely recessed to form an aperture of a diameter slightly less than the diameter of the shank whereby said shank may be frictionally engaged to retain the button in position upon the fabric.

6. The combination with a button having a shank adapted for insertion through fabric and the like, of a securing member comprising a rim; a pair of clamping elements formed from inwardly disposed extensions formed upon the rim and having proximate edges recessed to receive and frictionally engage said shank, said extensions being outwardly offset from the rim to provide gripping edges by which said clamping elements may be sprung outwardly to release said shank.

7. The combination with a button having a shank adapted for insertion through fabric and the like, of a securing member adapted for retaining said button in position upon said fabric, said securing member comprising a rim; an apertured backing element secured upon the front of said rim; a pair of inwardly disposed extensions formed upon the rim and rearwardly offset from the backing element to form clamping elements having proximate edges recessed to form an aperture of a diameter slightly less than the diameter of the shank, said clamping elements being adapted to be sprung rearwardly to grip the shank when the securing member is moved onto the said shank.

8. As an article of manufacture, a securing means for buttons having a shank, said securing means comprising a gripping element consisting of an annular ring, the center portion of which is stamped to form a pair of rearwardly offset clamping elements having proximate edges thereof recessed to form a centrally disposed aperture, said clamping elements being adapted to be sprung rearwardly to grip a button shank when forced through said aperture; and a backing element consisting of an annular ring provided with a flange arranged to be crimped over the gripping element ring and having a diametrically disposed bar having

an aperture registering with the recesses of the clamping elements.

9. As an article of manufacture, a securing means for buttons having a shank, said securing means comprising a gripping element consisting of an annular ring, the center portion of which is stamped to form a pair of rearwardly offset clamping elements having proximate edges thereof recessed to form a centrally disposed aperture, said clamping elements being adapted to be sprung rearwardly to grip a button shank when forced through said aperture; out-

wardly offset ends formed upon the clamping elements to provide gripping means by which said clamping elements may be sprung to release the shank; and a backing element consisting of an annular ring provided with a flange arranged to be crimped over the gripping element ring and having a diametrically disposed bar having an aperture registering with the recesses of the clamping elements. 15

In witness whereof I hereunto set my signature.

CHARLES MENDLER.
